UNITED STATES PATENT OFFICE.

JOHN H. GAVIN, OF CHICAGO, ILLINOIS, ASSIGNOR TO L. WOLFF MANUFACTURING COMPANY, OF CHICAGO, ILLINOIS, A CORPORATION OF ILLINOIS.

DESIGN FOR A LAVATORY.

No. 37,519.

Specification for Design.

Patented Aug. 29, 1905.

Application filed February 27, 1905. Serial No. 247,619. Term of patent 14 years.

To all whom it may concern:

Be it known that I, JOHN H. GAVIN, a citizen of the United States, residing in the city of Chicago, in the county of Cook and State of Illinois, have invented a new, original, and ornamental Design for a Lavatory, shown in the accompanying drawings, forming a part of this specification.

Figure 1 of the drawings is a perspective view of a lavatory, showing my new and or-

namental design therefor. Fig. 2 is a plan view, the spigots being omitted.

I claim—

The ornamental design for lavatory, as shown.

JOHN H. GAVIN.
